UNITED STATES PATENT OFFICE.

WALTER BURNHAM, OF CHICAGO, ILLINOIS.

STEAM-JACKET CONNECTION.

SPECIFICATION forming part of Letters Patent No. 394,825, dated December 18, 1888.

Application filed February 21, 1888. Serial No. 264,809. (No model.)

To all whom it may concern:

Be it known that I, WALTER BURNHAM, of Chicago, in the county of Cook and State of Illinois, have invented certain new and useful 5 Improvements in Steam-Jacket Connections; and I do hereby declare that the following is a full, clear, and exact description thereof, reference being had to the accompanying drawings, and to the letters of reference marked 10 thereon, which form a part of this specification.

This invention has for its object to provide a steam-jacketing for engine-cylinders, steam-pipes, water-tanks, &c., and to secure the 15 return of the water of condensation from the steam-jacketing space to the generator.

The invention is an adaptation of that illustrated and described in certain applications for patent filed by William Irving February 20 7, 1888, Serial Nos. 263,224 and 263,225, by which he has provided for the return of water 25 of condensation and entrainment from a steam-pipe to the generator. For this purpose Mr. Irving connects with the steam-pipe a return-pipe having a descending part or leg which terminates in an open end beneath the water-level of the generator. In this terminal leg of the Irving return-pipe a column of 30 water rises from the generator to a height necessary to equilibrity of pressure between the generator and the space in the return-pipe above said water column, which space above the water column is in steam communication with the generator and is under less 35 pressure than the steam-pipe, so that the excess of pressure in the steam-pipe produces a movement of steam toward the low-pressure chamber in the return-pipe. In the swift passage of the steam to the low-pressure 40 chamber small bodies of water of condensation and entrainment which enter the return-pipe from the steam-pipe are swept along with the steam and delivered into the descending leg of the return-pipe, where it joins 45 the water column and ultimately enters the generator.

My invention has for its object to adapt this principle to the perfection of steam-jackets for engine-cylinders, steam-pipes, water-tanks, 50 and other similar purposes.

Referring to the accompanying drawings, Figure 1 represents in end elevation an en-

gine having a jacketed cylinder and steam-chest, a generator in transverse vertical section, a tank having an inclosed steam-space 55 or steam-jacket surrounding it, also in transverse vertical section, a jacketed steam-supply pipe, connections for the supply of steam to the engine, to the jacket of the engine-cylinder, to the jacketing of the steam-supply 60 pipe, and to the jacketing of the tank and for the return of the water of condensation of the several jackets. Fig. 2 is an enlarged central vertical section of the steam-supply pipe and the lower end of the steam-jacket 65 thereof, together with the lower end of the pipe for the return of the water of condensation from said jacket, being a section in the line 2 2 of Fig. 3. Fig. 3 is a horizontal section in the line 3 3 of Fig. 2.

A represents a generator; B, a steam-engine; C, a steam-supply pipe leading from the generator to the interior of the engine-cylinder; C', a valve in said steam-pipe, and C² the exhaust-pipe.

The engine-cylinder and steam-chest are provided with a steam-space surrounding them, (indicated exteriorly by the letter B'), of the usual or any desired construction. To this jacketing-space surrounding the engine-cylinder leads a pipe, C³, from the steam-pipe C, said pipe C³ having a valve, C⁴. From the lower part of the steam-jacket space of the engine-cylinder leads a pipe, D, which rises to a point above the water-level in the generator A, and thence descends into the water-space of said generator, where it terminates in an open end, d. For convenience, the descending portion of the pipe D is separately marked D', and will be briefly called the "leg" 90 of the return-pipe.

D² is a stop-valve in the upper part of the leg D'.

D³ is a check-valve above the valve D² and near it, (here shown as being in the elevated transverse part of the return-pipe D, which may be called the "leader.") In the leader of the return-pipe is located a drain-pipe, D⁴, provided with a valve, d', these features of the return-pipe corresponding generally with 100 the preferred construction shown by Irving in his before-mentioned applications for patent. The operation of the return-pipe D is also that which is fully described by Irving and briefly

recapitulated in the foregoing portion of this specification—that is to say, the generator being under steam-pressure and the return-pipe having been emptied of water and prepared for operation by blowing off through the cock d' , steam entering the pipe C^3 from C and filling D condenses or escapes above the water in the leg D' , with the effect of causing a rapid movement of steam through the pipe C^3 , cylinder-jacket B' , and return-pipe D , in which movement of steam the water of condensation formed in the cylinder-jacket is carried in small detached bodies upward through said pipe D , and is deposited in the leg D' of said pipe. There is thus provided a constant and active circulation of live steam through the jacket-space surrounding the engine-cylinder, while the condense-water of such steam is promptly returned to the generator. Similar connections are shown with a steam-jacket, C^5 , applied to the steam-supply pipe C , the pipe supplying steam to the jacket-space between C and C^5 being shown at C^6 , and the return-pipe (answering to the pipe D already described) being shown at D^5 . The pipe D^5 will in practice be usually required to lead upward higher than shown in the drawings to give suitable length of leg to contain the water column without overflow of the latter into the ascending part of the return-pipe.

In order to take the water very completely from the jacket-space surrounding the steam-pipe C , the construction shown in Figs. 2 and 3 may be employed, in which the return-pipe D^5 connects into the side of the jacket-shell, and the latter is provided with an interior depending hood, c , which connects at its sides and top with the jacket-pipe and reaches very nearly to the bottom of the jacket-space. This hood forms an interior extension of the return-pipe, and in the sweep of steam beneath it all or practically all of the water of condensation will be swept out of the jacket-space.

E represents any form of vessel surrounded wholly or in part by a jacket, E' , giving the steam-tight jacket-space e . With a suitable point of this space e is connected a steam-supply pipe, E^2 , provided with a valve, E^3 . The pipe for the return of water to the generator may be of the simple form of construction and connection shown at D^5 , or of that shown at D as connected with the engine-cylinder jacket. I have, however, illustrated in connection with the tank-jacket e a special form of return-pipe connection, which may be used with any other jacket. In this case D^6 , D^7 , and D form the return-pipe for the jacket e of the tank E , and D^8 is a pipe leading from the steam-space of the jacket e into this return-pipe below and near the junction of D^6 with D^7 . The pipes D^6 and D^7 are shown provided with valves d^2 d^3 , respectively; but the latter of these is merely incidental to the connection of the tank-jacket e with the same return-pipe D that leads from the jacket B' of the engine-cylinder. The same is true of the

valve D^9 in the pipe D located in advance of the connection of D^7 with D .

When the engine-cylinder is disused, the valves C^4 and D^9 may be closed, and, on the other hand, when the tank-jacket is disused the valves E^3 and d^3 may be closed. The valve d^2 and the valve D^{10} in the steam-discharge pipe D^8 are, however, desirable to the proper or to the most economical operation of the discharge-pipe connections of a jacket comprising both pipes D^6 and D^8 . The pipe D^6 has a drainage-connection with the jacket-space e . As it delivers into the same pipe, D^7 , with the steam-pipe D^8 , an excessive outflow of steam may be prevented by so far closing the valve d^2 as to allow only water to escape through it, and the valve D^{10} may be also so far closed as to permit only enough steam to pass it to carry forward the water from D^6 . If the system embracing the engine and tank or other jacketed vessel or chamber, both connected with a single return-pipe, be employed, the steam from one jacket may be made to carry forward the water of condensation from both jackets. For example, in the case of the engine-cylinder and the tank-jackets of the drawings, having a common return-pipe, D , the steam-pipe D^8 in the tank-jacket may be disused or omitted and the water from said jacket e may be sent forward by the steam from the jacket B' . In this case the valve d^3 in the drain-pipe D^6 may be made serviceable by being set to deliver only water, or water with little steam, through D^6 , so that steam may be correspondingly economized.

The provision of a steam-pipe answering to D^8 or leading from the steam-space of a chamber to be drained and into a pipe, D^6 D , for the lifting of water taken from the chamber, is made the subject of another application for patent filed by me of even date herewith.

I claim as my invention—

1. The combination, with a steam-generator and an engine-cylinder or other inclosure provided with a steam-jacket space, of a pipe or pipes supplying steam to the jacket-space and a pipe leading from said space back to the generator and containing a liquid column, whereby a circulation is induced and maintained outwardly through the steam-supply pipe leading to the jacket and back to the generator through the return-pipe.

2. The combination, with a steam-generator and an engine-cylinder or other inclosure provided with a steam-jacket space, of a steam-supply pipe leading to the jacket-space and a return-pipe having drainage-connection with the jacket-space and leading to a point above the water-level of the generator, and thence downward to the generator for a distance sufficient to contain the water column due to the difference in pressure between the generator and the space in the return-pipe above the water column.

3. The combination, with a steam-generator and an inclosure provided with a steam-jacket

space, of a steam-supply pipe leading to the jacket-space, a return-pipe having drainage-connection with the jacket-space, and having an ascending and a descending portion, the latter of which terminates in the generator, and is provided with a liquid column of height due to the difference between the pressures above and below it, whereby the water formed in or taken into the circuit is delivered into the generator.

4. The combination, with a steam-generator and a steam-pipe leading therefrom, of a jacket-space surrounding the steam-pipe, a steam-supply pipe leading into one end of the jacket-space, and a return-pipe leading from the other end of the jacket-space to the generator and containing a water-column in its delivery end, whereby a steam circulation is in-

duced and maintained through the jacket-space.

5. The combination, with a generator, a vessel or inclosure provided with a steam-jacket space, and a steam-pipe leading to said space, of a return-pipe having drainage-connection with the jacket-space and leading to the generator and a pipe leading from the steam-occupied part of the jacket-space into the return-pipe.

In testimony that I claim the foregoing as my invention I affix my signature in presence of two witnesses.

WALTER BURNHAM.
